UNITED STATES PATENT OFFICE.

GÉZA SZÉKELY, JOHN GYULAY, AND ANDREW MAJLÁTH, OF NEW YORK, N. Y.

ADJUSTABLE DOUBLE TOOTHBRUSH.

Application filed November 17, 1927. Serial No. 233,755.

This invention relates to a new and useful improvement in tooth brushes adapted for the purpose of cleaning the teeth in a more thorough manner and more rapidly, promoting dental hygiene.

The object of the invention is to provide an improved tooth brush embodying certain new and novel features hereinafter more fully described, claimed and illustrated in the accompanying drawing.

Fig. 1 is a front elevational view of our improved tooth brush.

Fig. 2 is a fragmentary perspective view.

Fig. 3 is a side elevational view thereof.

Fig. 4 is an enlarged fragmentary view of the detachable brush member, illustrating in particular the means of attaching the same to the brush proper.

Fig. 5 is a top plan view of the detachable brush member.

Fig. 6 is a fragmentary side elevational view illustrating in particular a further development of our improved device.

Fig. 7 is a transverse sectional view taken on the line 7—7 of Fig. 6.

Fig. 8 illustrates another form of the handle of our improved device.

As here embodied our improved tooth brush comprises a brush member proper consisting of a handle element 10, of square transverse section having an extended element 11, of somewhat larger transverse section, preferably circular. The handle element 10, is provided with an enlarged head 12, or extremity, formed convex, of semi-circular construction, and provided with side extended elements 13 and 14, positioned oppositely. The said enlarged head 12, having its central portion 15, somewhat depressed, so as to form a rim at the edges thereof. The said side extended elements 13 and 14, providing a recess 16, or opening, adapted to accommodate the tongue of the person using our improved tooth brush. Bristles 17, such as ordinarily used for tooth brushes, are affixed to the outer edge of the enlarged head 14, and are radially downwardly disposed therefrom.

The removable brush member, is of similar construction to the enlarged head of the brush member proper, similar reference numerals denoting similar elements thereof. The said removable brush member is formed concave, so as to engage, or brush the outer surfaces of the teeth, adjacent to the lips of the person. The bristles 18, are affixed

to the outer edge of the removable brush member, and are angularly upwardly disposed therefrom.

The central portion 15, of the removable brush member, has formed therein an opening 19, adapted to receive the handle element. The said central portion 15, is provided with a lug element downwardly extended therefrom. The pawls 22, are pivotally mounted on the pins 23, secured to and extended from the lug element 20. The pawls 22, are provided with inwardly protruding portions 24, held in engagement with any desired pair of the notches 25 and 26, by means of the springs 27, mounted on the pins 28, secured to the lug element. The pawls 22, are provided with extended elements 29, adapted to be engaged by the thumb or finger of a person, as a means of disengaging, or removing the removable brush member proper. The above described construction is such as will permit the removable brush member to be removably attached to the handle element of the above mentioned brush member proper, so as to secure any desired space intermediate the bristles affixed to the said removable brush member and to the said brush member proper, to accommodate the teeth of the person using our improved tooth brush. It is understood that the bristles affixed to the brush member proper will engage or brush the inner surface of the teeth, adjacent to the throat.

It will be understood that the enlarged head of the handle member is formed or bent on a smaller arc than the above mentioned removable brush member, so as to provide a larger clearance at the extremities. The above described construction is such as will permit same to more readily and easily engage over the teeth to be cleaned, and which at the same time will more securely engage the teeth at the central portions of the said enlarged head and removable brush member, at which portion greater rigidity is present.

In Figs. 6 and 7, of the accompanying drawing, we have shown an engaging member 30, having formed therein an opening 31, adapted to receive the handle element 10 of the above mentioned brush member proper, as a means of slidably mounting the said engaging member 30, thereon. The engaging member 30, has formed therein openings 32 and 33, oppositely positioned, adapted to receive the extended elements 29 of

the above mentioned levers 22. The above described construction is such as will permit the protruding portion 24 of the levers 22, to be securely held in engagement with the notches 25 and 26, formed in the handle element 10, when the engaging member 30, is forced upwardly by the thumb or finger of the person using our improved device.

In Fig. 8 of the accompanying drawing, 10 we have shown a handle member 34, having formed therein, at or near one extremity thereof notches 25' and 26', adapted to receive the protruding portions 24 of the pawls 22, as a means of removably attaching the 15 removable brush member to the handle member 34. The above described construction is such as will permit the outer surfaces of the teeth to be cleaned or brushed.

Having thus described our invention what 20 we claim as new and desire to protect by Letters Patent of the United States is as follows:—

1. In a tooth brush of the class described, 25 a handle element provided with an enlarged head, bristles affixed to and extended angularly downwardly therefrom, a removable brush member having formed therein an opening adapted to receive the said handle element, notches formed in the said handle element, lugs on the removable member, levers pivotally mounted on pins secured to and extended from the lug elements, said levers held in engagement with the notches formed in the said handle element by means 30 of springs pivotally mounted on pins secured to and extended from the said lug elements of the said removable brush member.

2. In a tooth brush of the class described, 40 a handle element provided with an enlarged head of curved construction, and having side extended elements, and a central depressed portion for forming a recess to accommodate a user's tongue, bristles affixed to and extended radially downwardly therefrom, a re-

movable brush member having formed there- 45 in an opening adapted to receive the said handle element, notches formed in the said handle element, lugs on the removable member, levers pivotally mounted on pins se- 50 cured to and extended from the lug ele- ments, said levers held in engagement with the notches formed in the said handle element by means of springs pivotally mounted on pins secured to and extended from the said lug elements of the said removable 55 brush member.

3. In a tooth brush of the class described, 60 a handle element provided with an enlarged head of curved construction, and having side extended elements, and a central de- 65 pressed portion for forming a recess to ac- commodate a user's tongue, bristles affixed to and extended radially downwardly there- 70 from, a removable brush member having formed therein an opening adapted to re- 75 ceive the said handle element, notches formed in the said handle element, lugs on the removable member, levers pivotally mounted on pins secured to and extended from the lug elements, said levers being held in engagement with the notches formed in the said handle element by means of springs pivotally mounted on pins secured to and 80 extended from the said lug elements, an en- gaging member slidably mounted on the said handle element, openings formed in the said engaging member, said openings being adapted to receive the extended elements of the said levers, as a means of securely hold- 85 ing the inwardly protruding portions of the said levers in engagement with the said notches formed in the said handle element.

In testimony whereof we have affixed our signatures.

GÉZA SZÉKELY.
